AMMUNITION CHEST

Wilson C. Broga, Westfield, Mass.

Application July 28, 1944, Serial No. 547,091

7 Claims. (Cl. 89—34)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to improvements in ammunition chests for machine guns.

It is realized that ammunition chests for machine guns have heretofore been made both for unassisted ammunition chests, which normally consist of box-like receptacles for storing ammunition belts and from which the action of the gun withdraws the ammunition unassisted, and for assisted ammunition chests, in which a spring or springs assists in moving the ammunition toward the discharge slot and thereby decreases the drag on the ammunition belt so that it is safely within the limit of the machine-gun's pulling capacity.

It is well known that ammunition chests of the unassisted type are of very limited effective capacity, particularly because of the drag caused by pulling the ammunition belt through an excessive distance and height. In order to overcome this objectionable drag, it has been customary to apply or use springs in various ways in order to assist the movement of the ammunition belt towards the discharge slot and thus increase the effective carrying and delivering capacity of the chest.

In this way, the amount of ammunition that may be stored and effectively delivered from an ammunition chest is considerably increased. However, at the same time both the size and weight of such chests are obviously increased and chests of the prior art of equal capacity having these aforementioned spring arrangements have been considerably more complicated and more expensive to manufacture, all of which, of course, makes them objectionable.

It is therefore one of the principal purposes of this invention to provide an improved ammunition chest for machine-guns that will not only more effectively store and deliver a considerably greater amount of machine-gun ammunition than the currently used types of unassisted chests but which will be proportionally lighter in weight and of smaller size and less expensive and less complicated to manufacture than the so-called spring-assisted chests of the same capacity.

The specific nature of the invention as well as other objects and advantages thereof will clearly appear from a description of a preferred embodiment as shown in the accompanying drawings in which:

2

Fig. 1 is a longitudinal sectional view through a construction embodying the features of the invention.

Fig. 2 is a sectional view on the line 2—2 of Fig. 1; and

Fig. 3 is a partial top elevational view with the cover removed.

In Fig. 1 there is shown in assembled relation an ammunition chest embodying the specific novel features of this invention. The chest comprises a case member 1 provided with a cover 2 attached thereto by means of any desired type of hinge 3 and there may be a snap fastener, such as 4, for holding the closure in place.

15 The longitudinal section of case 1, as in Fig. 1, shows it to be in the form of an oblique parallelogram. It is to be understood that while, according to the preferred embodiment the case has acute angles of approximately 73 degrees, 20 this angle may be anywhere between say 90° and 60°, or even less if so desired.

25 The case will be provided with the usual means at one end (the right hand end in Fig. 1 and the means is not shown) for attaching the same to a machine gun. It has opposite vertical end faces or walls 5 and 6 and a bottom wall 7. The bottom wall preferably slopes upwardly away from the gun, or end wall 5, at any angle from the horizontal. In the end wall 5 adjacent the gun is provided a discharge slot 8 and a lip 9 for purposes to be described.

30 Within the case 1 is a U-shaped liner 10 formed to have a bottom wall 11 and side walls 12. The bottom wall or section 11 of said liner 10 is provided with a plurality of pairs or sets of ribs 14 and the side walls have a plurality of pairs or sets of ribs such as 15a, 15b, 15c, 15d, 15e, and 15f. The ribs of said latter pairs extend inwardly towards one another in substantially the same transverse plane with one another as shown.

35 A series of spacers such as 16a, 16b, 16c, 16d, 16e, and 16f are provided for assembly in the liner as shown in Fig. 1. These said spacers are provided with roll portions 18 at their bottom ends and preferably have stiffeners or beads 19 at their top ends.

40 Resilient wing parts, such as 20a, 20b, 20c, 20d, 50 20e, and 20f, extend outwardly from opposite vertical edges of spacers, 16a through 16f inclusive, near the top ends thereof as shown. Prior to assembly of the belt of cartridges in the chest, all of the wings preferably curve slightly forward, then bend at approximately 90° forward

and finally curve outward as illustrated in the case of wing 20b shown in Fig. 3.

Each spacer member is assembled in the case member 1, or liner 10, by means of a pin 26, which engages the spaced ribs 14 and rolls 18 of the spacers (see Fig. 2) forming therewith hinges around which the spacers can swing forwardly and downwardly to a forwardly reclining position against the next forward member as shown in Fig. 1, but not necessarily backward beyond the vertical position, as will appear. To insure the necessary stiffness required for spacers 16a through 16f, there may be provided thereon a pair of braces 27 as shown in Fig. 2.

The spacers 16 have been designated from front to back as 16a, 16b, and 16c and so on as are the 15 series of retainers and the 20 series of wings. As shown in the preferred embodiment, the spacer 16a is two cartridges shorter and spacer 16b is one cartridge shorter than those to the rear; also wings 20a on spacer 16a are located in alignment with the second, instead of the third, cartridge down so as to prevent interference in the forwardly inclined position and also prevent obstruction of discharge slot 8 as will be later apparent.

It is furthermore to be understood that while the 15 series of ribs or retainers are illustrated as being only slightly longer than wings 20, they may be the full height of liner walls 12, thereby also functioning as stiffeners of the said side walls 12. Also, side walls 12 of liner 10 may be eliminated and the retainers 15 may be formed in the sides of case 1, if so desired.

In either event, liner 10 and spacers 16 may be made of relatively thin sheet-spring stock, so that only very slight increase in weight results.

To load the chest, the last spacer, 16f, is held upright and the ammunition belt is placed over it with the end of the belt extending to the bottom of the chest (Fig. 1). A loop is then formed in front of the spacer with the third cartridge down, 25f, engaged between the pair of wings designated by 20f, expanding them and thereby locking said spacer 16f behind ribs 15f, the loop extending to the bottom of the chest and up again over the spacer 16e, which is next forward.

Proceeding in this manner, the chest is filled by looping said ammunition belt over successive spacers to form loops therebetween. In each case, the appropriate cartridge is secured between the wings of the corresponding spacer, thereby locking the spacer in an upright position and securing the portion of the belt of cartridges in back of said spacer. When the final loop has been formed in front of spacer 16a, the end of the ammunition belt is folded back above the forward spacers, where it is readily accessible when wanted.

It will be appreciated that each pair of wings are so spaced apart that when a belt of cartridges is suspended over the upright spacers 16 et al., with a link 24 disposed approximately horizontally across the top of spacer, 16f, for example, then a third cartridge down, such as 25f, will be between wings 20f so as to spread them outwardly and in back of retainers or ribs 15f, so that as long as cartridge 25f remains in place between the wings 20f, the said wings will engage the retainer and the spacer cannot swing forwardly but instead will be retained in upright position.

As ammunition is withdrawn from the chest and the cartridge between the wings of each succeeding spacer is withdrawn from engagement

therewith, the wings successively retract, clearing the 15 series of ribs and allowing the spacers to successively swing forward into a forwardly inclined position, thereby freeing the loop of ammunition that was behind the spacer. In this manner, the entire belt of ammunition is progressively released as needed. Furthermore, as the spacers fall forward, they form a generally upwardly curving floor over which the ammunition belt is drawn so that instead of lifting straight up, the belt is provided with an inclined support, over which the belt and ammunition slide.

Since the bottom wall of the chest normally slopes upwardly away from the gun, the lower end of each spacer is progressively higher than the one before it, thereby holding the ammunition belt in progressively higher position as it is withdrawn from the farther end of the chest. With the floor 11 sloping upwardly away from the chest at approximately 17° to the horizontal, the pivotal center of a tenth spacer back, in the construction illustrated, would be substantially at the level of feed slot lip 9, the low point of the auxiliary floor being not more than four cartridge spaces below that level, hence the lifting factor would be substantially eliminated for cartridges drawn from the rear portion of the chest, i. e., from greater distance from the cartridge feed slot. This creates a mechanical advantage which tends to neutralize the drag caused by increase in distance, thru which ammunition has to be withdrawn and greatly increases the amount of ammunition that can be efficiently fed from an unassisted chest.

While the preferred embodiment is shown as having six spacers accommodating loops of about twenty cartridges and the upward slope of the bottom of the chest is shown as approximately 17° from the horizontal, it is to be distinctly understood that these figures in no way limit the application of the invention, but rather only exemplify it, and that they may be varied in any way without departing from the scope of the invention.

It is also to be understood, that an ammunition chest embodying this invention is equally applicable to a belt consisting of metallic links or a fabric belt. Furthermore, any increase in the slope of the bottom of the chest will tend to increase the possible length of the chest from which ammunition can be effectively withdrawn, but at the same time, an excessive length of chest will require a support of some conventional form in order to support the greater weight at one side of the gun.

It is apparent, therefore, that the construction shown and described will serve to accomplish the objects stated above, but that said constructions disclosed are merely illustrative of the invention and not limiting, as various modifications therein may be made without departing from the invention as defined by a proper interpretation of the claims which follow.

I claim:

1. An ammunition chest for a belt of cartridges comprising in combination, a case member including vertical side walls and a bottom wall extending therebetween, said side walls having a plurality of pairs of oppositely disposed, inwardly extending spaced vertical ribs, a plurality of transversely disposed spacers having their lower ends pivotally mounted adjacent said bottom wall intermediate said pairs of vertical ribs for pivotal movement, said spacers being constructed and arranged to form a series of supports for a belt

of cartridges suspended in loops therebetween, each of said spacers having a pair of oppositely disposed resilient wings adjacent the upper end thereof, said wings being constructed and arranged to be pressed outwardly by the belt of cartridges engaged therebetween, said wings engaging said vertical ribs in their said outwardly pressed position, thereby locking said spacers in upright position.

2. An ammunition chest for a belt of cartridges comprising in combination, a case member including a bottom wall, vertical side walls and a forward end wall, said forward end wall being adapted to be secured to a machine gun, said bottom wall sloping upwardly away from said forward end wall, a plurality of transversely disposed rearwardly spaced spacers having their lower ends pivotally mounted adjacent said bottom wall for pivotal movement forward from normally vertical positions, said spacers being constructed and arranged to form a series of supports for the belt of cartridges suspended in loops therebetween, each of said spacers having a pair of oppositely disposed resilient wings adjacent the upper end thereof, said wings being constructed and arranged to be pressed outwardly by the belt of cartridges suspended over said spacers, and means within said case member cooperating with said outwardly pressed wings for respectively locking said spacers in vertical position.

3. An ammunition chest for a belt of cartridges comprising in combination, a case member including a bottom wall, vertical side walls and a forward end wall, said end wall being adapted to be secured to a machine gun, said bottom wall sloping upwardly away from said forward end wall, said side walls having a plurality of pairs of oppositely disposed, inwardly extending spaced vertical ribs, a plurality of transversely disposed rearwardly spaced spacers having their lower ends pivotally mounted adjacent said bottom wall intermediate said pairs of vertical ribs for pivotal movement toward the machine gun from normally vertical positions, said spacers being constructed and arranged to form a series of supports for the belt of cartridges suspended in loops therebetween, each of said spacers having a pair of oppositely disposed resilient wings adjacent the upper end thereof, said wings being constructed and arranged to be pressed outwardly by one of said cartridges, said wings engaging said vertical ribs in their said outwardly pressed position, thereby locking said spacers in upright position.

4. An ammunition chest for a belt of cartridges comprising in combination, a case member including a bottom wall, vertical side walls and a forward end wall, said forward end wall being adapted to be secured to a machine gun, said side walls having a plurality of pairs of oppositely disposed, inwardly extending, uniformly rearwardly spaced vertical ribs, a plurality of transversely disposed spacers having their lower ends pivotally mounted adjacent said bottom wall intermediate said pairs of vertical ribs to form a series of supports for the belt of cartridges suspended in loops therebetween, said bottom wall sloping upwardly away from said forward end wall whereby said spacers are mounted in progressively higher relation rearwardly, said spacers being constructed and arranged to successively pivotally move to a forwardly reclining position, to form an auxiliary floor, each successive spacer forming a floor portion of decreased slope and increased height for slidably supporting the belt of cartridges in its withdrawal movement into the machine gun, and

means constructed and arranged to cooperate with the belt of cartridges for locking said spacers in vertical position behind said vertical ribs.

5. An ammunition chest for storing and supplying a belt of cartridges to a machine gun comprising in combination, a case member including a bottom wall, vertical side walls and a forward end wall adapted to be secured to a machine gun, said side walls having a series of oppositely disposed, inwardly extending, uniformly rearwardly spaced vertical ribs, a plurality of transversely disposed spacers pivotally mounted adjacent said bottom wall intermediate said vertical ribs to form a series of supports for a belt of cartridges suspended in loops therebetween, said spacers being provided adjacent their upper ends with oppositely disposed forwardly extending resilient wings, said wings being constructed and arranged to be pressed outwardly by a cartridge in the belt of cartridges suspended over said spacers, said wings in their said outwardly pressed position engaging said vertical ribs to lock said spacers in vertical position, said bottom wall sloping upwardly away from said forward end wall whereby said spacers are mounted in progressively higher relation rearwardly and thereby successively pivotally move to a forwardly reclining position, to form an auxiliary floor, each successive spacer forming a floor portion of decreased slope and increased height for slidably supporting and guiding the belt of cartridges in its withdrawal movement from the chest.

6. An ammunition chest for a belt of cartridges comprising in combination, a case member including vertical side walls and end walls and a bottom wall extending therebetween, the forward of said end walls having a cartridge discharge slot at the upper portion thereof, said side walls having a plurality of pairs of oppositely disposed, inwardly extending spaced vertical ribs, and a plurality of transversely disposed spacers having their lower ends mounted adjacent said bottom wall intermediate said pairs of vertical ribs for pivotal movement between an upright position in which said spacers are retained by said pairs of ribs and a forwardly inclined position against the next forward spacer when said spacers are successively released from behind said pairs of ribs, all adapted and arranged whereby said spacers in the upright position serve as supports for holding the belt of cartridges suspended in loops therebetween and in the forwardly inclined position serve as an auxiliary floor for slidably supporting the loops of cartridges in a vertically decreasing slope with respect to said discharge slot.

7. An ammunition chest for a belt of cartridges comprising in combination, a case member including vertical side walls and end walls and a bottom wall extending therebetween, the forward of said end walls having a discharge slot near the upper end thereof, a plurality of transversely disposed spacers having their lower ends pivotally mounted adjacent said bottom wall for successive pivotal movement toward said discharge slot, and means for temporarily retaining said spacers in an upright position, said spacers constructed and arranged to be successively released from behind said retaining means whereupon said spacers pivot forwardly to form an upwardly curving auxiliary floor for facilitating the slidable passage of the cartridge belt through said discharge slot, said bottom wall sloping upwardly away from said forward end wall whereby said spacers are mounted in progressively higher relation rearwardly to decrease the amount of cartridges lying beneath

the horizontal plane of said discharge slot as the unsupported length of the cartridge belt is increased by the successive inclination of said spacers.
